J. BOGARDIUS.

6903X Metallic Mill

Patented Jan. 18, 1832.

Jan 18, 1832

* James Bogardus

Letters Patent (Date Jan. 18, 1832)

The Schedule referred to in these Letters Patent, is and making part of the same, containing a description in the words of the said James Bogardus himself of his improvement in the "universal mill" for grinding Paints, Drugs, Dye stuffs, corn, Rye, Wheat, Barley, oats, and various substances.

To all whom these Presents shall come,

James Bogardus of the city, County, and State of New York, and
Granting.

Be it known that the said Bogardus have made and invented, constructed as applied to use, a new and useful improvement in mills, called the "Universal Mill" from the variety of its actions and applications, for grinding Paints, Drugs, Dye stuffs, corn, Rye, Wheat, Rice, Barley, oats, and various other substances, and specified in the following words, to wit:-

My invention or improvement consists of a Frame, which for grinding, Paints &c may be made similar to the one in the annexed drawing, marked No 1, drawing A and for grain or other substances, similar in construction to Mills, built for those purposes with a Box made in a suitable manner, to catch the article ground as it is thrown from the stones in grinding, or in any other way that convenience or fancy may dictate.

No 2. The upright shaft, to which the stone is attached, and to which the power is to be applied either by means of a Wheel and Pinion as shown in the drawing A, or a belt passing over the pulley on the shaft as shown in drawing B which other method is best, adapted to the velocity required.

No 3. The shaft above, for what is termed in common mills "the tail stone" is fastened firmly in a horizontal position to the top of the shaft.

No 3. and may be made to any convenient size, but for ordinary purposes it is recommended not to be over twenty inches diameter. In many instances metallic substances may be used in place of stone.

No 4. The top stone, or what is commonly called the runner, may also be made of the same material as the shaft stone, and is to be placed on the top of the stone a little off the centre, the distance to be determined by the article to be ground, and the points required. It is recommended to be about one fifth less in diameter than the shaft stone, but may be varied without destroying the effect, and is secured by a screw or lever at No 5, running into a pivot hole in the bridge No 10, made for that purpose and placed firmly in the centre of No 4. The runner is drawn by the motion of the shaft stone each revolving on its own axis, and by being placed off the centre gives it a peculiar motion which causes it to grind with great rapidity.

No 5. The screw, or lever, with a point passing through a slide to be placed in a crane or beam in a suitable manner for the purpose of shifting the runner to or from the centre, of giving its proper and passing it in its proper place.

No 6. The hopper wheel may be made in the same manner as those of mills for the same purpose.

No 7. The bolster thru' which the shaft No 2 passes and holds it in its right position. It should be placed near the under side of the shaft stone.

No 8. The step into which the lower point of the shaft No 2 runs.

No 9 - the crane or beam through which the screw passes down on the bridge No 10 to give the stone No 4 the desired pressure.

No 10. The bridge in which point No 5 is received. It should be made of iron with the pivot hole of steel tempered in suitable manner and fastened firm in stone & No 4.

What I claim as my invention is the manner of placing the two Nos 4 of the centre of the shaft stone No 2 which produced a combination of

of motions that I believe to be hitherto unknown and cannot be easily
described.

New York December 11, 1831

James Bogardus.
